COIN DELIVERY MACHINE

Arnold R. Buchholz, Watertown, Wis., assignor to Brandt Automatic Cashier Company, Watertown, Wis., a corporation of Wisconsin

Filed Oct. 4, 1957, Ser. No. 688,163

7 Claims. (Cl. 133—4)

The invention relates to coin delivery machines.

The main object of the invention is to provide an electrically operated coin delivery machine of an improved type over that of the prior U.S. Patent No. 2,406,948, of September 3, 1946, to Hoffman et al. In said prior patent the operation of any key of the keyboard acted to set one or more of the coin ejectors in position for ejector operation by a motor drive. According to the present invention, the operation of any key of the keyboard acts to control the operation of an electrically operated means to position one or more of the coin ejectors in position for ejector operation by an electrically operated actuator, whereby only a light touch on the keys is necessary and is consequently less fatiguing to the operator of the machine.

A further object of the invention is to provide a single electrical power source for actuating the clutch controlling the connection of another power source with the ejector operating means.

A further object of the invention is to provide an improved ejector operating means.

This application is a continuation in part of my prior application Serial No. 581,581, filed April 30, 1956, for Coin Delivery Machine, now abandoned and includes certain improvements over said prior application, said improvements being the elimination of certain parts that were operated by the lock release key and acted on the motor switch and the inclusion of an additional switch in the control circuit of the machine which acts in advance of the motor control switch and prevents recycling of the machine in case the operator does not fill a depleted coin channel directly after the machine is stopped because of a coin depletion.

The invention further consists in the several features hereinafter described and more particularly defined by claims at the conclusion hereof.

In the drawings:

Fig. 1 is a top plan view of a coin dispensing machine embodying the invention;

Fig. 2 is a vertical sectional view taken on the line 2—2 of Fig. 4, parts being broken away;

Fig. 3 is a horizontal sectional view taken on the broken line 3—3 of Fig. 2;

Fig. 4 is a horizontal sectional view taken on the broken line 4—4 of Fig. 2;

Fig. 5 is a vertical sectional view taken on the line 5—5 of Fig. 4;

Fig. 6 is a detailed vertical sectional view of parts shown in Fig. 2 showing them in a different position;

Figs. 7 and 8 are detailed sectional views taken along the line 7—7 of Fig. 4 showing certain parts in different positions;

Fig. 7a is a detailed side elevation view of parts shown in Fig. 7 as viewed along the line 7a—7a of Fig. 7;

Fig. 9 is a detail view taken approximately in the same plane as Fig. 7, and illustrates the respective parts of Figs. 7 and 8 in relative position just prior to release

2

of certain switch holding elements actuated by projecting cam members operated by rotation of the prime mover drive shaft.

Figs. 10 and 11 are detailed vertical sectional views of parts shown in Fig. 2 showing them in different positions;

Fig. 12 is a circuit wiring diagram;

Fig. 13 is a view similar to Fig. 2 showing the parts in a coin ejecting position.

10 Fig. 1 shows a keyboard such as is used on a machine for paying out the amount of change indicated on the keys in the form of coins such as pennies, nickels, dimes, quarters and half dollars. Such a machine is called a payer. In some instances, the keys may represent the difference between the purchase amount and a dollar or certain predetermined fractions thereof and is then designated as a changer. The invention herein is applicable to either form of machine. There are 15 ninety-nine keys K on the general keyboard and special keys 5, 10, 25, 50 and 100, a depletion release key DR and a current supply control switch CS mounted thereon. The keys are mounted in the upper portion of the machine as is also a coin tray T having coin receiving channels A, B, C, D, E, F, G and H. Channels A, B, 20 C are for pennies, channel D for nickels, channels E and F for dimes, channel G for quarters and channel H for half dollars. The keys K are of known construction and spring operated to a release position, and their details 25 may be found in the following U.S. patents: Brandt No. 1,850,198, dated March 22, 1932, and Brandt No. 1,822,560, dated September 8, 1931. The keys are designed to provide one or more projections P, each of which is disposed over a rocker R. Each rocker R is pivotally 30 mounted on pins 1 mounted in the side frame members 2 of the machine and held against the key or keys by a spring 3 (see Fig. 2).

35 Referring to Figs. 2 and 4, a power driven rotary shaft 4 is journaled in bearings 5 supported from the base of the machine and has crank discs 6 at opposite ends 40 thereof, each disc carrying an eccentrically disposed roller 7. Channel bar members 8 have pad portions 9 engaged by the rollers 7 so that on each partial rotation of the shaft 4 these members are thrust forwardly. At 45 its front end each bar 8 is suspended from the frame of the machine by a link 10, and intermediate its ends each bar is pivotally and slidably supported by a roller 11 mounted on a bracket 12 and working in its channel. A transversely extending shaft 13 connects the outer 50 ends of said bars together and at each end is pivotally connected to the lower end of one of the links 10 whose other end is pivoted on a pin 10a mounted in the side frame of the machine. A spring 13a connected to a shaft 31 acts to hold the bars 8 against their rollers 7 so that they are reciprocated as the shaft 4 turns.

55 Coin ejector members or fingers 14, one for each coin channel, are pivotally mounted on the shaft 13, said fingers working in slots 15 in said channels. Each finger is yieldingly supported on the upper side of a lever 16 pivotally mounted on a fixed shaft 17 and urged upwardly by a spring 18 interposed between said lever and its shaft support. Each shaft 17 carries a lever 19 which at its outer end is pivotally connected at 20 to one end of a link 21 whose other end is pivotally connected to a crank arm 22 on its associated rocker R. Downward swinging movement of the rocker acts through the link 21 to swing lever 19 clockwise and thereby engage and swing lever 16 upwardly to move its associated ejector finger 14 upwardly to bring it into a coin ejector position so that when the bars 8 are thrust forwardly by the rollers 7, the lowermost coin or coins in the associated coin channel will be pushed out into a delivery chute

23, as shown in Fig. 13. The chute 23 has a discharge opening controlled by a sliding door 24 normally closed by a spring 25.

Each of the rockers R has a finger portion 26 adapted when the rocker is swung down by the depression of a key to move into position adjacent a shoulder 27 on a rack or toothed bar 28. The bar 28 is mounted on spaced supporting links 29 so as to move generally parallel to the lower ends of the keys, said links being connected together by a spring 30. When on the depression of a key, one or more of the rockers R is moved from the position shown in Fig. 2 to the position shown in Fig. 10 and the bar 28 is shifted to the left as indicated in Fig. 11, the fingers 26 will be engaged by the teeth of the bar 28 so that the rockers R will be swung clockwise to position the ejector members 14 in their coin dispensing position.

The shaft 4 may be driven by a suitable electrically operated prime mover. As an example and referring to Fig. 4, I have shown an electric motor M having a reduced speed output shaft 31 carrying a bevel gear 32 meshing with a bevel gear 33 having a hub loose on shaft 4 and provided with a clutch face 34 adapted to be engaged by the clutch face 35 of a clutch sleeve 36 slidably mounted on shaft 4 and slotted at 37 to engage a pin 38 on said shaft. Sleeve 36 has a collar 39 receiving the forked end of a bell crank lever 40 pivotally supported at 41 and having its other end operatively connected by a link 42 to one arm of a pivotally supported solenoid-operated lever 43 normally urged to its inoperative position by a spring 44 and pivotally connected to the forked end of the plunger P of a solenoid S. Plunger P carries a collar 45 forming the backing of a cushioning disc pad 46. The other arm of the lever 43 is operatively connected by a link 47 with one of the links 29. Energization of the solenoid S pulls plunger P inwardly to swing lever 43 and consequently lever 40 to shift clutch sleeve 36 to engage the clutch faces 34 and 35 to rotate the shaft 4 and at the same time said lever acting through the link 47 and links 29 acts to shift the bar 28 to the left to move the engaged rockers R and their crank 22 to bring ejector fingers 14 into dispensing position so that as the shaft 4 turns to operate these fingers as previously described they will dispense coins from their associated channels. Instead of a motor and its associated clutch, a rotary type solenoid or a reciprocatory type solenoid having a suitable crank connection with the shaft 4 may be used without departing from the invention.

Referring to Fig. 12, current supply lines 48, 48a and 49 are connected to the terminals of the motor M and the coil of solenoid S is connected across the lines 48 and 49. The line 49 has included therein the switch CS, interlock switch IS, a normally open motor switch MS and a normally closed coin depletion actuated switch CD.

Referring to Figs. 2, 4 to 7 and 7a, a U-shaped lever 50 is pivotally connected at its ends 51 with suitable bracket arms 52 and is normally urged by a tension spring 53 connected to an arm 54 on said lever into engagement with the lower edges of the rockers R which extend over the top of the transverse portion of said lever. For the sake of clearness, lever 50 is not shown in Fig. 2 or Fig. 13 but is shown in Figs. 4 and 7. The swinging down of any rocker R by the depression of its associated key acts to swing the lever 50 downwardly about its pivots. The switch IS is a normally closed switch that is held in open position when the lever 50 is in its upper position by the engagement of the arm 54 with the actuator 54a of said switch. The swinging down of any rocker R by the depression of its associated key acts to swing the lever 50 downwardly about its pivots and swing the arm 54 out of engagement with the actuator 54a allowing the switch IS to close.

A dog 55 is loosely pivotally mounted on a pin 56 mounted in the transverse portion of lever 50 so that on the downward swinging movement of lever 50 and

after the switch IS closes, the dog 55 will engage a post 57 on the actuator arm 58 for the motor switch MS and move this arm to close this switch. When this occurs, the arm 58 is held in closed position by a latch 59 pivotally mounted on the frame at 60 and normally urged to a latching position by a spring 61. The cooperative latch surfaces are a shoulder 62 on the latch and a projection 63 on the arm. The latch 59 holds switch MS closed until a pin 64 on a collar 65 on shaft 4 moves around to engage and move a lever 67 which engages the dog 55 and swings it away from the post. Lever 67 is pivotally mounted intermediate its ends at 68 on the frame and normally urged to a stop position clear of the dog 55 by a spring 69. Shortly after the dog 55 is swung past the post 57, and before the lever 59 is released by the rockers R to permit switch IS to be opened thereby, a pin 70 on the opposite side of the collar 65 moves into engagement with a projecting foot 66 on the latch 59 to release its engagement with projection 63 on arm 58 so that the actuator 58 may move to its "off" position to open the motor circuit.

In coin handling machines, means are generally provided to prevent further operation of the machine in case the coins in any one of the channels become depleted to such an extent as to need replenishment. Usually this mechanism stops the machine just before a coin channel is exhausted so that the operator by pressing a depletion release key can secure one or more payments before replenishing the depleted channel. For accompanying this purpose, a coin engaging finger or lever 72 is pivotally mounted at its upper end to work in a slot 73 in each coin channel, Figs. 2 and 6. Each finger 72 is yieldingly urged against the stack of coins by one arm of a bell crank lever 74 pivotally mounted on a transversely extending shaft 75 and whose other arm 76 is engaged by a spring pressed pin 77 mounted in guides on the back of the tray support. A U-shaped bar or rod 78 is pivotally mounted in the side frames of the machine and urged upwardly into contact with the arms 76 of the levers 74 by a spring 79. When in the event of a coin depletion any one of the fingers 72 is free to swing inwardly of its coin channel, its associated lever 74 is swung clockwise so that its arm 76 engages the transverse portion of the bar 78 and swings it downwardly into engagement with a pivoted switch actuator lever 80 and moves this lever to open the switch CD which thereby opens the motor circuit to stop the operation of the machine. Under normal operating conditions on each operation of the machine as the ejector operating bars 8 are moved forwardly, a transversely disposed rod 81 carried by brackets 82 on these bars moves forwardly or toward the left and engages with extensions 83 of the levers 74 to swing these levers counterclockwise against the pressures of their spring pressed pins 77 so that the fingers 72 are relieved of pressure so that the coins engaged by these fingers can drop down to a position where they can be pushed out of their channels. When as noted above the coins in any one of the channels become depleted and the motor is stopped, another operation of the machine can be had by the operator's first pressing down the depleted release key DR and then pressing the coin dispensing control key. Depression of the key DR acts to move a lever 84 pivotally mounted intermediate its ends on a pin 85 mounted on one side of the machine, and when its key engaging end is swung down, its other arm 86 swings up releasing a spring actuated lever 87 pivotally mounted at 88 on the frame of the machine and having a cam or inclined surface 89 which engages the transverse portion of the bar 78 and swings this bar upwardly out of engagement with the depletion release switch actuator 80 to allow switch CD to close and so that said bar 78 will act to swing the arms 76 of the levers 74 upwardly to relieve pressure of the levers on the fingers 72. This establishes a temporary normal operating relation of the parts of the ma-

chine so that on depressing the desired coin dispensing control key the machine will operate once more and will then be stopped by the coin depletion mechanism above described. The ejector fingers 14 are mounted in spaced relation on the rod 13 between spacer sleeves 90, one of these sleeves being in the plane of movement of the lever 87 so that as the bars 8 and fingers 14 move forwardly during a coin dispensing operation, the upper end of said lever is swung toward the left away from the arm 86 of the lever 87.

It is to be noted that since the motor M and the coil of solenoid S are both operated by the closing of the switch MS by the depression of any one of the keys K and that this switch MS is latched closed, that once a key is depressed, the machine will go through its dispensing cycle and the depression of any other key during this period will have no effect and will not disturb the position of the rockers R.

From the above description, it will be noted that the ordinary operation of the machine occurs when the operator, after closing the switch CS, presses down on any one of the keys K causing its projection P to engage one or more of the rockers R and swing such rocker or rockers into engagement with the lever 50 to move said lever to release switch IS so that it can close and then act through the dog 55 to move the motor switch MS into its latched position and energize the coil of solenoid S at the same time that the rockers R are brought into operative association with the toothed bar 28, all the switches CS, IS, MS and CD then being closed. The solenoid S shifts lever 43 to throw in the clutch for shaft 4 and also shifts the rockers R that are down to cause them to act through the links 21 to set the desired ejector fingers 14 in coin dispensing position, and then as the motor M turns the shaft 4, the bars 8 and rod 13 with the ejector fingers 14 are moved toward the left as a unit, and those fingers which are in an operative position push the coins from their coin channels into the chute 23. As the shaft 4 continues to revolve and the ejectors move back, the pins 64 and 70 act as previously described to release the latch 59 and move the lever 67 to throw the dog 55 out of the way of the post 57 so that the switch actuator 58 can move to inoperative position to stop the motor and hence the movement of the shaft 4 as the ejectors 14 and bars 8 are returned to their initial position. The solenoid circuit, which is also opened by release of the switch MS will also permit the spring 44 to return the toothed bar 28 to return to the position shown in Fig. 2, thereby releasing the rockers R for upward movement by the action of the springs 3. This upward action will then permit the bar 50 to depress the switch actuator 54a and open switch IS. If a coin depletion occurs, the opening of the switch CD opens the motor circuit so that the machine cannot be operated, except as noted for one or two times through the operator's pressing down of the depletion release key DR before pressing down on the dispensing key K, and then it will be necessary for the operator to replenish the depleted coin channel for further dispensing operations. Replenishment of any completely depleted coin channel will act to relieve the pressure of lever 74 on bar 78 and hence on the actuator 80 of switch CD permitting it to close, but this will not permit a recycling of the machine since the switch IS is then open. As only a light pressure need be exerted on the key K to effect the initial movement of the rockers R and the closing of the motor switch, the operation of the machine is less fatiguing to the operator than that of the prior Patent No. 2,406,948, above referred to.

I desire it to be understood that this invention is not to be limited to any particular form or arrangement of parts except in so far as such limitations are included in the claims.

What I claim as my invention is:

1. In a coin delivery machine having coin channels and a keyboard having operator controlled keys, the combination of a coin ejector for each channel movable into and out of the plane of a coin to be ejected from its associated channel, means for positioning an ejector in its coin ejecting position, a movable rocker displaceable by one or more of said keys operatively connected with an associated ejector positioning means, a shiftable power operated means, distinct from said keys, to actuate any key selected rocker or rockers to operate its or their associated ejector positioning means, and power operated means for operating said coin ejectors.
2. In a coin delivery machine having coin channels and a keyboard having operator controlled keys, the combination of a coin ejector for each channel movable into and out of the plane of a coin to be ejected from its associated channel, means for positioning an ejector in its coin ejecting position, a movable rocker mechanically displaceable by one or more of said keys operatively connected with an associated ejector positioning means, a shiftable member adapted for operative engagement with one or more rockers upon displacement of said rocker or rockers by said keys, a prime mover controlled by said keys for moving said shiftable member to actuate any key selected rocker or rockers to operate its or their associated ejector positioning means, and power operated means for actuating said coin ejectors.
3. In a coin delivery machine having coin channels and a keyboard having operator controlled keys, the combination of a coin ejector for each channel movable into and out of the plane of a coin to be ejected from its associated channel, means for positioning an ejector in its coin ejecting position, a movable rocker mechanically displaceable by one or more of said keys operatively connected with an associated ejector positioning means, a shiftable member adapted for operative engagement with one or more rockers upon displacement of said rocker or rockers by said keys to actuate any key selected rocker or rockers engaged thereby to operate its or their associated ejector positioning means, a solenoid for moving said shiftable member, an electrical supply circuit for said solenoid including a key controlled rocker operated switch, and electrically operated means in said circuit for actuating said coin ejectors.
4. In a coin delivery machine having coin channels and a keyboard having operator controlled keys, the combination of a coin ejector for each channel movable into and out of the plane of a coin to be ejected from its associated channel, means for positioning an ejector in its coin ejecting position, a movable rocker controlled by one or more of said keys arranged for releasable mechanical engagement therewith for actuating an associated ejector positioning means, a shiftable member adapted for operative engagement with one or more rockers upon displacement of said rocker or rockers by said keys to actuate the key selected rocker or rockers thereby engaged, a rotary shaft, means operable by said shaft for actuating said coin ejectors, a solenoid for moving said shiftable member, an electrical supply circuit for said solenoid including a key controlled rocker operated switch, a rotary electrically operated prime mover in said circuit, a normally inoperative clutch arranged for operatively connecting said prime mover in driving relation with said shaft, and substantially concurrent means operatively connecting said solenoid and said clutch for actuation of said clutch into operative relationship of said prime mover with said shaft.
5. In a coin delivery machine having coin channels and a keyboard having operator controlled keys, the combination of a pair of spaced movable channel members, a transversely extending shaft mounted in said channel members, coin ejector members pivotally mounted in spaced relation on said shaft, there being an ejector member for each coin channel, a swingable support for the front ends of said channel members, a roller mounted in

the channel of each channel member and forming another support therefor, a rotary shaft having an eccentric connection with at least one of said channel members, key controlled means for operating said shaft, and key controlled means for selectively positioning said ejector members in an operative position relative to the coins in one or more of said coin channels.

6. In a coin delivery machine having coin channels, the combination of a coin ejector for each channel having an operative and inoperative position, power operated key controlled means for determining the operative position of an ejector relative to its channel, electrically operated means for operating said ejectors including a supply circuit, a normally open motor control switch and a normally closed interlock switch in said circuit, and key controlled means normally operative to hold said normally closed interlock switch in an open position and operable by the depression of a key to permit this switch to move to closed position and also operable to close said normally open motor control switch, said key controlled means being arranged to permit the closure of said interlock switch in advance of the closure of said motor control switch, and being further arranged to permit said interlock switch to return to normally open position in advance of the return of said motor control switch to its normally open position; whereby recycling

of said machine will be prevented on failure to replenish said coin channels upon depletion thereof.

7. In a coin delivery machine having coin channels and a keyboard having operator controlled keys, the combination of a coin ejector for each channel movable into and out of the plane of a coin to be ejected from its associated channel, means for positioning an ejector in its coin ejection position including a movable oscillatory rocker arranged for alternative direct actuation of a respective ejector into and out of its place of operation, a power operated shiftable rack bar and a releasable mechanical operating connection between said rocker and rack bar, said keys adapted to selectively actuate an associated rocker to establish the said operating connection, and power operated means for operating said coin ejectors upon establishment of said mechanical operating connection between a respective rocker and the said rack bar.
